UNITED STATES PATENT OFFICE.

JOSHUA W. CREGAR, OF PHILADELPHIA, PENNSYLVANIA.

AIR-CUSHION FOR VALVES.

SPECIFICATION forming part of Letters Patent No. 696,009, dated March 25, 1902.

Application filed February 4, 1901. Serial No. 45,884. (No model.)

To all whom it may concern:

Be it known that I, JOSHUA W. CREGAR, a citizen of the United States, residing at Philadelphia, in the county of Philadelphia and State of Pennsylvania, have invented certain new and useful Improvements in Air-Cushions for Valves, of which the following is a specification.

My invention relates to an air-cushion for valves, and has for its object to provide an air-cushion in extension from a point below the valve or water ingress to a point above the seat of the valve, so that the opening of the valve to allow a free flow of water through the spout will coincidentally therewith cause a compression of air both below and above the valve. The effect or result to be attained by my particular arrangement of air-cushion is, first, to react in producing a free flow of water through the spout, and, second, to effect the closure of the valve under a pressure of air induced by the pressure of water that, bearing upon the volume of water considerably below the spout-egress, will form a cushion for the water as the valve is returning to its seat, thereby causing the return to be of a movement to prevent the usual knock or hammer and consequent pounding and strain upon the pipe.

A further object is to produce these effects in a valve without the use of springs or other mechanical attachments extraneous to the valve proper.

A further object is to construct a valve and stem operative without the usual packing.

In my invention I have so simplified the construction as to produce a perfect self-closing noiseless valve with the employment of a single air-tube, upon which is secured the valve, with the extended upper closed end and the downwardly-projecting portion contiguous to the inflow, whereby the pressure of air is initial with the closing of the valve and continuous until the valve is opened.

The invention consists in the parts and combination of parts hereinafter described, and pointed out in the claim.

In the drawings, Figure 1 is a longitudinal vertical section of the device, showing the valve closed. Fig. 2 is a longitudinal vertical section of the air-pipe, showing the valve interposed intermediate its length.

I have illustrated my invention in connection with a basin-cock, in which 1 designates

the shell, formed with a globular head 2 and 55 spout 3 leading therefrom, with a diaphragm 4 extending partially across the globular portion. The upper end 5 of the shell is closed at 6 and recessed to receive the lever 7 for depressing the air-pipe 8, located within the 60 end 5 and longitudinally movable therein, the recesses being closed by an annular band 9. The lower portion of the shell is tubular and flanged at 10, there being a packing-nut 11 seated thereon when screwed into the annular screw-threaded portion 12 of a water-chamber 13, shouldered at 14 to receive a flexible valve-seat 15, of any suitable material, against which the valve 16 seats, the valve 16 being secured upon air-pipe 8 intermediate its length, with the reduced end 17 of the water-chamber screw-threaded to receive a nut, (not shown,) by which to secure the basin-cock to a base.

The operation will be apparent. Water being admitted into the end 17 of the water-chamber compresses the air into pipe 8 considerably below valve 16 and enters the same as far as water-pressure will compress the air, the flow to the water chamber and spout being in and through the annular space 18, around the air-tube 8, through the space formed by the annular neck of the water-chamber into the water-chamber, and finds egress through the spout, the air acting as a 85 cushion when the valve-stem is released and producing an equilibrium between the pressure of the water and the movement and force of the valve, whereby the usual pounding in the pipe is obviated and the valve is seated 90 quickly without injury to its seat.

What I claim is—

In a cushioned valve, a head and spout, a water-chamber having a connection for the water-pipe, secured to the head, a valve-seat 95 at the junction of the head and chamber, an air-tube extending through the head and chamber, a lever connected to the upper end of the air-tube, a valve on the air-tube intermediate of its length to engage the valve-seat substantially as described.

In testimony whereof I affix my signature in presence of two witnesses.

JOSHUA W. CREGAR.
